US0D1103757S

(12) **United States Design Patent** (10) **Patent No.:** **US D1,103,757 S**
(45) **Date of Patent:** **** Dec. 2, 2025**

(54) **PACKAGING FOR FOODSTUFF**

(71) Applicant: **COOPBOX GROUP S.r.l.**, Reggio Emilia (IT)

(72) Inventor: **Michele Divia**, Reggio Emilia (IT)

(73) Assignee: **COOPBOX GROUP S.R.L.**, Reggio Emilia (IT)

(**) Term: **15 Years**

(21) Appl. No.: **29/969,163**

(22) Filed: **Oct. 21, 2024**

(30) **Foreign Application Priority Data**

Aug. 8, 2024 (WO) WIPO151745

(51) **LOC (15) Cl.** **09-03**

(52) **U.S. Cl.**

USPC **D9/424; D7/602**

(58) **Field of Classification Search**

USPC ..... D9/414, 418, 420, 423, 424, 425, 426, D9/428, 429, 430, 431, 432, 433, 456, D9/457; D7/500, 550.1, 601, 602, 629 CPC ... (57) **CLAIM**

The ornamental design for a packaging for foodstuff as shown and described herein.

DESCRIPTION

FIG. 1 is a top perspective view of a packaging for foodstuff. FIG. 2 is a bottom perspective view of the packaging for foodstuff shown in FIG. 1.

FIG. 3 is a left view of the packaging for foodstuff shown in FIG. 1.

FIG. 4 is a right view of the packaging for foodstuff shown in FIG. 1.

FIG. 5 is a front view of the packaging for foodstuff shown in FIG. 1.

FIG. 6 is a back view of the packaging for foodstuff shown in FIG. 1.

FIG. 7 is a top view of the packaging for foodstuff shown in FIG. 1; and,

FIG. 8 is a bottom view of the packaging for foodstuff shown in FIG. 1.

1 Claim, 8 Drawing Sheets
